United States Patent Office

JOHN LUNGER, OF WALDO, OHIO.

Letters Patent No. 64,120, dated April 23, 1867.

IMPROVEMENT IN WAGON-SEAT SUPPORTER.

The Schedule referred to in these Letters Patent and making part of the same.

TO ALL WHOM IT MAY CONCERN:

Be it known that I, JOHN LUNGER, of Waldo, in the county of Marion, and State of Ohio, have invented certain new and useful Improvements in Wagon-Seat Supporters; and I do hereby declare that the following is a full, clear, and exact description of the same, reference being had to the accompanying drawings, and to the letters of reference marked thereon.

In the annexed drawing, making part of this specification, A represents one of the side-boards of a wagon-bed. B represents a metallic standard, which rests upon and is secured to this side-board, for supporting one side of the seat of the wagon. This standard has a bow formed at its upper end as seen, for the purpose of supporting and having the springs D secured to said standard. Below the loop or bow C is a hook, D, formed on one side of the standard; this hook catches upon the upper edge of the side-board A, as shown fig. 2. a a represent staples driven into the side-board A. The lower end of the standard B passes down into the staples a a and is by said staples and the hook D secured to the side-board. One of these standards is secured to each of the side-boards and the seat rests across the body on the springs D. It will be seen that by means of these standards with springs attached, the seat may be removed or placed upon the body in a very few moments.

Having thus fully described my invention, what I claim as new, and desire to secure by Letters Patent, is—
The standard B, constructed substantially in the manner set forth, and used as and for the purpose specified.
As evidence that I claim the foregoing I have hereunto set my hand in the presence of two witnesses.

JOHN LUNGER.
